UNITED STATES PATENT OFFICE.

HARRY O. DAVIDSON, OF CLEVELAND, OHIO, ASSIGNOR TO THE HYDRAULIC PRESSED STEEL COMPANY, OF CLEVELAND, OHIO, A CORPORATION OF OHIO.

SUPPORT FOR CONCRETE FORMS.

Application filed November 21, 1919. Serial No. 339,581.

To all whom it may concern:

Be it known that I, HARRY O. DAVIDSON, a citizen of the United States, residing at Cleveland, in the county of Cuyahoga and 5 State of Ohio, have invented a certain new and useful Improvement in Supports for Concrete Forms, of which the following is a full, clear, and exact description, reference being had to the accompanying drawings.

This invention relates generally to a support for flat slab concrete forms and more particularly to one composed of sheet metal and so constructed that the support as a 15 whole can be quickly and easily arranged for the purpose of supporting the slab pan thereon and one in which certain parts thereof can be quickly and easily removed in order to release said pan. Another object of the invention is to provide a support which can be arranged at any point along the joist and brought into supporting engagement with the pan at any portion of the side thereof.

20 With these objects in view and certain others which will become apparent as the description proceeds, the invention consists in the novel features of construction of the various parts and in the manner of combining or arranging said parts into cooperative relation, all of which will be fully described hereinafter and set forth in the appended claims.

In the drawings forming a part of this 35 specification, Fig. 1 is a sectional view partly in elevation showing the practical application of one embodiment of my invention; Fig. 2 is an elevation taken on the line 2—2 of Fig. 1; Fig. 3 is a detail perspective view of one of the stirrups; Fig. 4 is a detail perspective view of one of the supporting arms or brackets and Fig. 5 a 40 sectional elevation showing a slightly modified construction.

45 In carrying out my invention I employ a plurality of joists A which are arranged in parallel relation and spaced apart a distance determined by the width of the flat slab pan B which is to be arranged between 50 said joists and supported therefrom. Sheet metal stirrups C are shaped to straddle said joists and are arranged thereon at definite points and the legs of said stirrups are bowed outwardly as shown at C'.

55 In connection with each stirrup I employ

a pair of oppositely disposed supporting arms or brackets D made also of sheet metal, each supporting arm or bracket comprising a base plate which is slotted vertically as shown and central upper portions projected 60 upwardly providing a vertical finger D' and end portions turned horizontally providing supporting fingers D². A central portion is bowed outwardly as shown at D³ and the intermediate end portion is bowed inwardly 65 as shown at D⁴ thereby providing a loop D⁵ in the base plate and it will be noted that the upper half of the base plate is bent outwardly as shown at D⁶ in order to space the fingers D' and D² some distance from 70 the upper end of the joist and, if desired, strengthening corrugations D⁷ may be made at the juncture of the horizontal fingers D² and the inclined portion D⁶. The bowed portion C' of the stirrup leg is adapted to fit 75 into the bowed portion D³ of the base plate and a locking wedge E is then inserted through the loop D⁵ and within the bowed portion C' of the stirrup leg, thereby securely locking the supporting arm to the stirrup. The 80 flat slab pan B is arranged upon the supporting arms, the sides thereof contacting with the vertically positioning fingers D' while the bottom flanges or edges rest upon the horizontal fingers D² and in order to 85 prevent any movement of said pan I employ a plurality of spring clips F which are sprung over the bottom flanges of the pan and the horizontal supporting fingers D² as most clearly shown in Figs. 1, 2 and 5. 90

After the pans have been properly positioned, filling strips G are arranged upon the joist as shown and these filling strips are preferably made tapering so that they can be wedged in between the pans to form 95 a perfectly tight fit thus aiding in locking all the forms together across a definite area. In Figs. 1 and 2 it will be noted that the sides of the pan are bent inwardly and that the positioning fingers D' contact with said 100 inwardly bent portions. In Fig. 5 however the sides of the pan are not only pressed inwardly but are also apertured to receive the vertical finger D⁸ which in this instance is considerably longer than the finger D' extending practically to the top of the pan as most clearly shown. This provides an additional element of safety in the connection of the pan with the supporting arms.

In operation the stirrups are placed upon 110

the joists and the supporting arms or brackets are attached thereto on opposite sides by means of the locking wedges and the pans are placed upon the supporting arms and the 5 spring clips fastened to the pan and arms to connect said parts together. The filling strips are then forced in, completing the unbroken slab form throughout the given area.

After the concrete has been poured and 10 permitted to set for a definite period of time, say twenty-four or forty-eight hours, the flat slab pans can then be removed and used again where desired, and in order to remove said pans it is only necessary to disconnect 15 the spring clips, knock out the wedges and the supporting arms can be withdrawn from the stirrup and the pan is then free to be taken down, the filler strips remaining supported upon the joists.

20 A form support constructed as shown herein and described is simple in operation and inexpensive in manufacture and furthermore can be arranged at any point desired upon the joists in order to engage the 25 pan at any desired points.

Having thus described my invention, what I claim is:-

1. The combination with a stirrup each 30 leg of which is bowed, of a pair of supporting arms comprising a looped base plate provided with upwardly and outwardly project-

ing fingers and a locking member adapted to be inserted between the leg of the stirrup and the base plate of arm and through the loop of said base plate.

35

2. The combination with a stirrup, of a supporting arm, said stirrup and arm having overlapping portions and the locking member longitudinally inserted between said overlapping portions.

40

3. The combination with a pan, of a stirrup, and a support detachably connected to said stirrup, said support having vertical and horizontal fingers at its upper end and with which the pan contacts.

45

4. The combination with a stirrup having a bowed portion, of a supporting arm having a looped portion adapted to register with the bowed portion of stirrup, a wedge engaging said bowed and looped portions, the upper end of said arm having a vertical and a horizontal finger, and a pan engaging 50 said fingers.

50

5. The combination with a pan having bottom flanges, of supporting arms having fingers upon which said pan rests, means for supporting said arm, and clips adapted to engage said fingers and pan flanges as set forth.

55

In testimony whereof, I hereunto affix my 60 signature.

HARRY O. DAVIDSON.
